UNITED STATES PATENT OFFICE.

JULIUS ERDOES AND ELMER SAS, OF NEW YORK, N. Y., ASSIGNEES TO THE METALLOGRAPH CORPORATION, OF NEW YORK, N. Y., A CORPORATION OF NEW YORK.

NAPKIN-RING.

1,339,180.

Specification of Letters Patent.

Patented May 4, 1920.

Application filed July 18, 1919. Serial No. 311,792.

To all whom it may concern:

Be it known that we, JULIUS ERDOES and ELMER SAS, citizens of the United States and Hungary, respectively, and residents of 5 New York, in the county of Bronx and New York, respectively, and State of New York, have invented certain new and useful Improvements in Napkin-Rings, of which the following is a specification.

10 The present invention relates to napkin-rings, that is to say to rings for holding table-napkins, when not in use.

The main object of the invention is to produce a napkin-ring, that is provided 15 with a tag-holder, the latter forming part of the body of the ring, thereby not interfering with the proper operation of the ring.

Another object of the invention is to provide 20 a napkin-ring of the character mentioned, wherein the tag-holder serves at the same time to keep the ends of the body portion of the ring in operative relation to each other.

25 A further object of the invention is to devise a ring of the character specified, which is simple in construction, efficient in operation, and which can be manufactured on a commercial scale or, in other words, 30 one which is not so difficult to produce as to be beyond the reasonable cost of such a contrivance.

With these and other objects in view, which will more fully appear as the nature 35 of the invention is better understood, the same consists in the combination, arrangement and construction of parts hereinafter described, pointed out in the appended claims and illustrated in the accompanying 40 drawings, it being understood that many changes may be made in the size and proportion of the several parts and details of construction within the scope of the appended claims without departing from the 45 spirit or sacrificing any of the advantages of the invention.

One of the many possible embodiments of the invention is illustrated in the accompanying drawings, in which:—

50 Figure 1 is a plan view of a napkin-ring, constructed in accordance with the present invention; Fig. 2 is an elevation thereof; Fig. 3 is a front elevation of a portion of the ring and the tag-holder in position thereon, on a larger scale; Fig. 4 is a section taken

on line 4—4 of Fig. 3; Fig. 5 is a section taken on line 5—5 of Fig. 3; Fig. 6 is a front elevation, on a larger scale, of that portion of the ring body which receives the tag-holder; Fig. 7 is a section taken on 60 line 7—7 of Fig. 6; Fig. 8 is a front elevation, on a larger scale, of one element of the tag-holder; and Fig. 9 is a section taken on line 9—9 of Fig. 8.

The napkin-ring, shown in the drawings, 65 consists, generally speaking, of a body portion 10 and a tag-holder 11. The ring may have any suitable shape, as usual in constructions of this type, in the case illustrated it being of oblong configuration, the spaced 70 ends 12 of its body portion being connected by the tag-holder. The ring is made, preferably, of metal by stamping operation. Adjacent each body end, there is formed thereon a substantially U-shaped extension 75 13, that is spaced from the respective end and extends in parallel relation thereto, as clearly appears from the several figures of the drawings. These extensions are, preferably, made integral with the body 10 by 80 stamping and then bent out of the plane of the said body. The bases 14 of the U-shaped extensions are disposed parallel to each other, they running in parallel relation to the axis of the ring.

85 Between the body ends 12 and the extensions 13 is disposed the tag-holder 11, the latter comprising a back plate 15 and a front plate 16. These plates are of equal size and of oblong configuration, their 90 heights corresponding substantially to the height of the body portion of the ring and their lengths being such as to completely fill the space between the outwardly projecting inner ends 17 of the extensions 13. 95 The back plate is preferably unbroken, while the front plate is provided with an opening 18, through which the label 19, bearing an inscription 20, appears, the said label being interposed between the said two 100 plates. The front plate 16 is provided with two parallel, outwardly extending projections 21, which are adapted to engage with the inner edges 22 of the bases 14 of the extensions 13. The projections 21 are made, 105 preferably, integral with the front plate 16, they being formed by stamping.

The operation of this device is as follows:—In assembling the ring, first the front plate 16 is inserted between the body 110

ends 12 and the outwardly projecting extensions 13 thereon. The back plate and label are then placed into positions, forcing the front plate outward, so that the projections 21 thereon are caused to bear against the inner edges 22 of the bases 14 of the said extensions. The front and back plates prevent thus the body ends 12 from approaching one another, the projections 21, on the other hand, preventing a separation of the said ends, as the folded table-napkin is inserted into the ring. The tag-holder has thus a two-fold function, to wit: It serves, first, as the means for keeping the label in position on the ring, and, second, as the means for preventing a movement of the body ends 12 both toward and away from each other.

It is obvious that, while herein a particular tag-holder has been described and a specific means has been disclosed for holding the same in position upon the ring, other constructions may just as well be employed without departing from the invention, which lies mainly in the provision of a tag-holder that forms part of the ring, it being insertible and removable, at will.

The construction herein described is particularly useful in view of the fact that the napkin-rings are usually provided with decorations while in flat strip form. They are then bent into ring shape. If the ring ends were to be united by solder, the solder-

ing or other uniting operation might seriously interfere with the decorations on the 35 ring. By providing a tag-holder of the type indicated, the uniting operation is done away with, the said tag-holder constituting a uniting means that does not necessitate heating of the ring ends. 40

What we claim is:—

1. A napkin-ring, comprising a body portion having spaced ends provided with outwardly projecting extensions, said extensions being spaced from said ends and running in parallel relation thereto, and a tag-holder detachably mounted between said extensions and said body ends. 45

2. A napkin-ring, comprising a body portion having spaced ends provided with outwardly projecting substantially U-shaped extensions, said extensions being spaced from said ends and running in parallel relation thereto, and a tag-holder fitting between said extensions and body ends, said tag-holder comprising a back plate abutting against said body ends and the extensions thereon, and a front plate having projections engaging opposite edges of said extensions. 50

Signed at New York, in the county of New York, and State of New York, this 14th day of July, A. D. 1919.

JULIUS ERDOES.
ELMER SAS.
